United States Patent Office

Des. 224,598
Patented Aug. 8, 1972

224,598

CHRISTMAS TREE

Joseph T. Gelardi, Yonkers, N.Y., assignor to American Technical Industries, Inc., Mount Vernon, N.Y.

Filed Nov. 5, 1969, Ser. No. 19,951

Term of patent 14 years

Int. Cl. D11—04

U.S. Cl. D29—1

FIG. 1

FIG. 2

FIG. 1 is a side elevational view of a Christmas tree showing our new design, the side opposite being substantially similar thereto; and

FIG. 2 is a perspective view of one of the branches of the tree.

I claim:

The ornamental design for a Christmas tree, as shown and described.
